PORTABLE SCAFFOLD

**Leonard C. Gasner and Claude M. Page, Chicago,
Ill.; said Page assignor to said Gasner**

Application June 17, 1948, Serial No. 33,476

1 Claim. (Cl. 280—44)

This invention relates

1

This invention relates to improvements in scaffolds and is directed to portable and adjustable scaffolds and is especially adapted to be employed in painting box cars, although the use thereof is not so limited, being equally capable of use in building maintenance, construction work, or aircraft repair, and a primary object of the invention is to provide a device that is capable of being readily transported from place to place, the height thereof being rapidly adjusted to work conditions.

Another object of the invention is to provide a device that is light, strong, flexible and sturdy, to eliminate the hazards of hastily built and temporary structures, where work is performed under precarious conditions.

A further object of the invention is to provide a scaffold that is quickly put together and dismantled, when needed and is compact in construction to occupy but little storage space when not being used.

And a further object of the invention is to provide means for retracting the rollers that enable the scaffold to be moved about so that the device now rests firmly on the ground and thereby eliminates danger of undesired movement while vigorous work is being performed upon it.

The invention accordingly comprises the features of construction, combinations of elements and arrangements of parts which are exemplified in the description hereinafter in connection with the accompanying drawings, and the scope of the application of which will be indicated in the following claim.

In the accompanying drawings, in which is illustrated one of the various possible embodiments of the invention:

Figure 1 is a side elevation of the scaffold; Figure 2 is a horizontal view taken substan-

tially on the line 2-2 of Figure 1;

Figure 3 is a top plan view of the invention; Figure 4 is an end elevation of the invention;

and
Figure 5 is a perspective, fragmentary detail of the pivot means for placing the rollers into operative position.

Referring to the figures, the scaffold of the invention is identified generally by numeral 10 and supports a work platform 12 on the upper extremity thereof.

Platform 12 rests on three pairs of rectangular blocks or stationary supports 14 when work is to be performed upon it. Of course, the total number of supports may vary, as may be de-

sired, the instant number having been found to represent ideal conditions. Secured vertically to blocks 14 are tubular sleeves or casings 16, sleeves 16 mounting the retractible members, 5 as will presently appear, and provide the means for adjusting platform 12 vertically. Sleeves 16 are of hollow construction and receive slidably therein platform support rods 18. Rods 18 are transversely slotted adjacent the bottom thereof 10 at 20, (Figure 1) and receive therein retaining pins 22 (Figure 2) when in adjusted position. Pin 22 is secured by a chain 24 to cross bar 26 extending transversely between each pair of standards or sleeves 16. This is done in order 15 to prevent possible loss of pin 22 when the scaffold has been dismantled for storage, or while it is being adjusted vertically. Standards 16 are apertured at 28 along the vertical length thereof whereby it is adapted to receive pin 22 20 in various positions of adjustment.

Rollers or casters 30, of which there are a total of six, as may be readily seen from Figure 2, are the means whereby the scaffold is transported from place to place, as desired. Casters 30 are arranged in pairs and are mounted transversely by shafts 32, shafts 32 also mounting yokes 34. Yokes 34 are secured, for each pair of casters 30 to short links 36, 38 and 40, for a purpose soon to become apparent. As may best be seen in Figure 4, an inverted U-brace 42 is secured to shaft 32 and retains a plate 44 thereon, plate 44 engaging a second similar plate 46. Plate 46 retains tubular caster bracket 48 and is pivoted for movement by means of pivot rod 50. It will be noted that casters 30 are adapted to extend slightly below blocks 14 when in vertical position. Handle 52 including hand grip 54, is pivotally secured at 56 by means of yoke 34 to casters 30 at one end thereof and is secured as by chain 58 to one end of link 36. Link 36 is pivoted at the opposite end thereof to pivot bar 60, bar 60 being of sufficient length to pivotally connect to the adjacent end of link 38. Link 38 is, in turn, secured to pivot bar 62, bar 45 62 being of similar construction to bar 60, and pivotally secured to the near end of link 40. Link 40 is integrally secured to the upper extremity of caster brackets 48. Thus, when handle 52 is actuated, by pivoting it forwardly, chain 58 will exert pull on link 36, causing the attached caster wheel 30 to pivot on pivot rod 50 into vertical position. This action moves bar 60 to move link 38 into horizontal position and therewith attach caster wheel 30, and in turn actuate bar 62 for similar movement of

link 40. In this manner, scaffold 10 is elevated from rest position on blocks 14 and the device is ready to be transported.

Cross braces 64 are secured to the upper and lower extremities of standards 16 and 66 and serve to strength the device and avoid shifting laterally thereon. Transverse braces 68 serve a similar function.

Ladder 70 is secured medially of scaffold 10, at each side thereof and terminates on platform 12 to be secured thereto by retaining bars 72. Transverse bar 74 is welded across to each ladder 70 and serves to retain it in rigid position at all times. Angle brackets 16 and braces 78 retain platform 12 on rods 18 and in fixed position.

Any suitable material may be employed, as is desired. It is, of course, to be understood that the details of structure and arrangement of parts may be variously changed and modified without departing from the spirit and scope of the invention.

Having thus described the invention, what is claimed as new is:

In a portable scaffold having an elongated platform, a frame carrying said platform and including vertically adjustable first and second end supports and a vertically adjustable central support, a transverse rod pivoted upon each of said supports, a tubular bracket secured to each rod, 30 said bracket having an upper end with an axial

slot therethrough and a lower end, a wheel having an axle rotatably supported on said lower end of said bracket, a short link secured in the slot of each of said brackets and extending laterally therefrom, a first longitudinal bar terminally pivoted to the short links carried by the brackets associated with the first end and central supports, a second longitudinal link terminally pivoted to the short links carried by the brackets associated with the central and second end supports, an elongated handle having a lower end rotatable on one of said end wheel axles, and a flexible connection secured between said handle and the short link on the bracket supporting said one end wheel whereby manual operation of said handle will urge all the wheels in unison to engage the ground and raise the supports therefrom.

LEONARD C. GASNER.
